UNITED STATES PATENT OFFICE.

GEORGE WASHINGTON STILES, OF SMITHMILL, PENNSYLVANIA.

CHURN-MOTOR.

SPECIFICATION forming part of Letters Patent No. 719,056, dated January 27, 1903.

Application filed May 25, 1901. Serial No. 61,850. (No model.)

To all whom it may concern:

Be it known that I, GEORGE WASHINGTON STILES, a citizen of the United States, residing at Smithmill, in the county of Clearfield and State of Pennsylvania, have invented certain new and useful Improvements in Churn-Motors, of which the following is a specification.

This invention relates to churn-motors; and it has for its object to provide an improved mechanism of this class which shall be superior in point of simplicity, positiveness of operation, and general efficiency.

In the drawings, Figure 1 is a side elevation of my improved churn-motor, showing the churn in operative position, one side of the casing being removed to better illustrate the construction. Fig. 2 is a detail vertical transverse sectional view taken upon the line xx , Fig. 1, and showing the spring-actuated operating member of the motor. Fig. 3 is a top plan view of the same.

Corresponding parts in all the figures are denoted by the same reference characters.

Referring to the drawings, 1 designates my improved churn-motor, which comprises a spring-actuated operating member 2 and a churn-cradle 3, which is operatively connected with the operating member 2 and upon which the churn proper, 4, is given the required oscillation or rocking movement. The entire motor is preferably supported upon a suitable base or table 5, which may be provided with legs or standards 6. The spring-actuated operating member 2 may be housed in a suitable casing 7, which is mounted upon one end of the table 5, and the cradle 3 is mounted upon the other end of the table in front of the casing 7.

In the preferred form of construction the cradle 3 consists of a horizontal frame 8, which is supported by short uprights 9 upon rockers 10, and the rockers fit between longitudinal guide-cleats 11, which latter are arranged upon the top of the table and at opposite sides of the same. The cradle is provided at the end adjacent the casing 7 with an upright fixed arm 12, by which the cradle may be oscillated. Operative connections, as at 13, extend between the fixed arm 12 and the operating member 2.

In the preferred form of construction the

spring-actuated operating member 2 consists of a main spring-driven shaft 14, a supplemental spring-driven shaft 15 in operative connection with the same, and a crank-shaft 16 in operative connection with the supplemental shaft 15. The operative connections 13 extend between the crank-shaft 16 and the fixed arm 12, carried by the cradle 3. The shafts 14, 15, and 16 are arranged in a vertical series, the shafts 14 and 16 occupying, respectively, the lowermost and uppermost positions and the shaft 15 occupying the intermediate position. The operative connections 13 between the cradle 3 and the crank-shaft 16 consist of a pitman or connecting-rod 17, one end of which is connected with the upper end of the upright arm 12 and the other end of which is connected with a crank-elbow 18, which is formed in the crank-shaft 16. The crank-shaft 16 is also provided with a fly-wheel 19. The shafts 14, 15, and 16 are arranged transversely of the casing 7 and are journaled at their ends, as at 20, in side members of the casing.

Loosely mounted upon the shaft 14 is a gear-wheel 21, and loosely mounted upon the shaft 15 is a gear-wheel 22. The gear-wheel 22 meshes with a pinion 23, which is fixed upon one end of the shaft 16, whereby the rotation of the gear-wheel 22 causes the rotation of the crank-shaft 16 and the consequent oscillation or rocking of the cradle 3 through the medium of the fixed arm 12 and the connecting-rod. A spring-drum 24 is coiled about the shaft 14, one end of the same being connected with said shaft 14, as at 25, and the other end thereof being connected with the gear-wheel 21, as at 26. This spring may be considered both as a prime mover and as a reservoir of power after it has been wound up, as will be hereinafter more fully explained. A ratchet-disk 27 is fixed to the shaft 14 at any convenient point clear of the other mechanism, and a pawl 28, which is carried by the casing 7, operates in connection with the ratchet-disk 27 to prevent rotation of the shaft 14 in one direction. The shaft 14 is also provided at one end with a crank 29, having a handle 30, whereby the crank may be operated to wind up the spring-drum 24 upon the shaft 14. The gear-wheel 21 meshes with a pinion 31, fixed to the shaft 15. A spring-

drum 32, similar to the spring-drum 24, but having a less number of convolutions and of weaker construction, is coiled about the shaft 15, and one end of the same is connected with the gear-wheel 22, as at 33, the other end thereof being connected with the shaft 15, as at 34. This spring, although it is really the one which imparts motion to and regulates the speed of the churn, must be considered as supplementary to and not the equal of the spring 24 on shaft 14. Each of the spring-drums 24 and 32 is inclosed between its respective gear-wheel 21 or 22 and a spider-shaped cage 35 and 36, respectively, which 15 cages consist of a plurality of radial arms 37, which are connected at their outer ends with the respective gear-wheels, and at their inner ends with hubs 38, which are revolubly mounted upon the respective shafts 14 and 15. 20 The relative arrangement and construction of parts are such that when the spring-drum 24 is wound up by means of the crank 29 it causes, through the revolution of the gear 21 and pinion 31, the revolution of the shaft 15. 25 in the proper direction to wind up the spring-drum 32 upon said shaft 15. The shaft 14 is prevented from counter revolution by the pawl 28 and ratchet-disk 27, and during such winding a hand held on the churn proper 30 prevents the revolution of the crank-shaft 16. The winding up of the spring-drum 32 being completed and the restraining-hand removed, the tension causes the rotation of the gear-wheel 22, which in turn, through the medium 35 of the pinion 23, causes the revolution of the crank-shaft 16 and the consequent rocking of the cradle 3 and the churning of the contents of the churn proper, 4. The momentum of the fly-wheel 19 causes a positive and steady 40 movement of the parts.

I have found the following relative sizes and proportions to be useful in arranging my two spring-drums and attaining the best results in combination; but they are not arbitrary. Let 45 both springs be of the same thickness or gage of metal. Make spring 24 two and one-half inches wide and forty feet long, but let spring 32 be only one inch wide and fifteen feet long. This would provide for approximately twenty- 50 four turns of the crank to completely wind up the large spring and would enable the small spring to communicate such power and momentum to the churn as would give approximately two thousand nine hundred and eighty 55 strokes by one winding of the large spring.

The churn proper, 4, may readily be removed from the cradle 3 for the purpose of filling, cleaning, or emptying of the same, and the churn proper may readily be locked against 60 endwise displacement by a pivoted latch 39, which may be connected with a suitable securing device 40, fixed to the upright arm 12 upon the cradle 3. The churn proper, 4, is securely retained in position by its abutment at 65 one end against the fixed arm 12 and at the other end against a transverse cleat 41, arranged transversely of the end of the cradle

opposite that with which the fixed arm 12 is connected.

The operation and advantages of my improved churn-motor will be readily understood by those skilled in the art to which it appertains. When the churn proper is in its position upon the cradle 3 and the crank 29 has been operated to wind up the spring-drum 24 upon the shaft 14, the gear-wheel 21 causes the rotation of the shaft 15, which in turn winds up the spring-drum 32 and rotates the gear-wheel 22 to cause the rotation of the crank-shaft 16 and the consequent rocking of the cradle 3 to perform the churning operation. The gear-wheel 22 is thus rotated through the medium of the spring-drum 32, and it results that the spring-drum 24 in running down or imparting energy to the spring-drum 32 winds the latter up to a considerable extent as well as rotating the gear-wheel 22. This surplus of energy after the spring-drum 24 becomes weaker than the spring-drum 32 causes the shaft 15 to revolve in a direction 85 the reverse of that in which it revolves under the expenditure of the energy of the spring-drum 24, and this reverse movement of the shaft 15 causes the gear 26 to revolve in such a direction that the spring-drum 24 becomes 90 partially wound up again. In the meantime the energy of the spring-drum 32 is also exerted to continue the revolution of the crank-shaft 16. When the spring-drum 32 becomes weaker than the spring-drum 24, the energy 95 accumulated by the spring-drum 24 exerts itself to rotate the gear-wheel 22 and the shaft 15 in the initial direction and again wind up the spring-drum 32 to continue the rotation of the crank-shaft 15, as before. It will be noted that 105 this continuous alternate winding and unwinding of the spring-drums 24 and 32 causes a combined operative effect of the two spring-drums, which results in a longer continued operation of the spring-motor than would follow from use of but one of the spring-drums. When both of the spring-drums reach the state in which they can no longer overcome 110 the resistance of the mechanism, the crank 9 is operated to again wind up the spring-drum 115 24 as initially and recommence the churning operation. The relation of the springs may be further explained by stating that the spring 24 can be wound up to its full extent even when the shaft 16 is being revolved by 120 the communicated power of spring 32, or shaft 16 may be held fast (by hand or any suitable device) while spring 24 is being wound up to its full extent, which being accomplished it will be found that spring 32 has 125 also been wound up to its full extent, but without strain. Upon release of the shaft 16 spring 32 comes into operation, while spring 24 practically remains inactive until the small spring commences to weaken. Then 130 the large spring operates to rewind the small one, and so the shaft 16 has always the full benefit of the co-operation of both springs.

The relative arrangement of parts in which

the casing 7 and the spring-actuated member 2 are arranged at one end of the table 5 and the cradle 3 and the churn proper, 4, are arranged at the other end of the table 5 is superior in 5 point of compactness and convenience. The churn-cradle 3 oscillates in a path longitudinally of the table or support 5 and is prevented from lateral displacement by the cleats 11, arranged upon the top and at the 10 sides of said tables.

I do not desire to be understood as limiting myself to the details of construction and arrangement as herein described and illustrated, as it is manifest that variations and 15 modifications may be made in the features of construction and arrangement in the adaptation of the device to various conditions of use without departing from the spirit and scope of my invention and improvements. I therefore 20 fore reserve the right to all such variation and modification as properly fall within the scope of my invention and the terms of the following claims.

Having thus described my invention, I 25 claim and desire to secure by Letters Patent—

1. In an improved churn-motor, a cradle for the churn proper, and a spring-actuated operating member operatively connected with 30 the same and comprising a main shaft, a supplemental shaft, a gear-wheel loosely mounted upon each of said shafts, a spring-drum for said main shaft and the gear-wheel which is mounted thereon, a spring-drum for said supplemental shaft and the gear-wheel which is mounted thereon, the ends of said spring-drums being connected respectively with the respective shafts and gear-wheels, said gear of said main shaft being operatively connected 35 with said supplemental shaft, and said gear on said supplemental shaft operatively connected with the churn, means for preventing the revolution of said main shaft in one direction, and devices for winding up said 40 spring-drum of said main shaft.

2. In an improved churn-motor, a cradle for the churn proper, and a spring-actuated operating member operatively connected with 45

the same and comprising a driven shaft and means for rotating the same consisting of two 50 spring-drums and devices for winding up one thereof, said spring-drums being so operatively connected that the unwinding of one thereof causes the winding up of the other thereof.

3. In an improved churn-motor, a cradle for the churn proper, and a spring-actuated operating member operatively connected with the same and comprising a driven crank-shaft provided with a fly-wheel, a connecting-rod 60 extending between the crank-shaft and the cradle, and means for rotating the crank-shaft consisting of two spring-drums and devices for winding up one thereof, said spring-drums being so operatively connected that 65 the unwinding of one thereof causes the winding up of the other thereof.

4. The herein-described churn-motor, comprising a base or support, a cradle for the churn proper arranged upon one end of the 70 base or support and comprising a frame provided with rockers, and a spring-actuated operating member arranged upon the other end of the base or support and operatively connected with the cradle, said member comprising 75 a main shaft rotatable in only one direction, a loose gear-wheel mounted on said shaft and a spring-drum secured at one end to said shaft and at the other end to said gear-wheel, a supplemental shaft provided with a pinion 80 meshing with said main-shaft gear-wheel, a loose gear-wheel mounted on said supplemental shaft, and a spring-drum secured at one end to the supplemental shaft and at the other end to its gear-wheel, a crank-shaft provided with a pinion meshing with the supplemental-shaft gear-wheel, and means for rotating the main shaft.

In testimony whereof I have signed my name in the presence of the subscribing witnesses.

GEORGE WASHINGTON STILES.
